D15-124. OR D12,000 EX

No OCT 26, 1880
12,000

UNITED STATES PATENT OFFICE.

CHARLES L. BELLAMY, OF ARLINGTON, NEW JERSEY.

DESIGN FOR A POLISHING-HEAD.

SPECIFICATION forming part of Design No. 12,000, dated October 26, 1880.

Application filed July 2, 1880. Term of patent 3½ years.

To all whom it may concern:

Be it known that I, CHARLES L. BELLAMY, a citizen of the United States, residing at Arlington, Hudson county, New Jersey, have 5 originated a new and ornamental Design for a Polishing-Head, of which the following is a specification, in connection with the accompanying engraving.

My design applies to those devices for carrying a buffing or polishing wheel, which usually consist of a standard surmounted by a journal-box, in which a horizontal spindle is rapidly revolved, one end of the spindle being fitted to receive an emery-wheel, while the opposite end terminates in a tapering screw to receive the buffing or polishing disks or brushes, the whole being mounted on a suitable stand, from which power is applied to revolve the spindle.

20 The figure in the annexed engraving presents a perspective view of my newly-designed polishing-head, in which *a* indicates the supporting-standard, which is fastened to a table, stand, or bench; *b*, the journal-boxes, extending laterally from the top thereof; and *c*, the spindle, which revolves therein.

The standard *a* is hollow, and its upper end encircles and incloses the middle part of the driving-spindle and the driving-pulley thereon, so that the driving-belt passing to and from the pulley, as well as the pulley itself, is inclosed and concealed thereby, and a more agreeable and finished appearance is given to the device.

The main feature of my design consists in 3 the form of the standard or pedestal *a* in the proximately pyramidal shape shown, tapering toward the top and terminating in a rounded or semi-cylindrical cap or capital, which is swelled beyond the tapering part of the top of 4 the pedestal, and is concentric with the spindle, or nearly so, while the journal-boxes *b* spring centrally from each side of the rounded top, and blend into the side thereof with a flaring conical form, as shown in the engraving. This design, while neat and simple, harmonizes the connection of the several parts, and imparts an attractive and pleasing appearance to the device.

I usually prefer to surmount the rounded 5 top of the pedestal with the figure of an eagle, as shown, or similar finial, to give the pedestal a more spirited appearance; but this may or may not be used.

What I claim as my invention is—

5. The specified design for a polishing-head, consisting of a pedestal of proximately pyramidal shape, terminating in a rounded top or capital, with the journal box or boxes springing centrally from the sides thereof, substantially as herein described and illustrated.

CHARLES L. BELLAMY.
